SERVING CRADLE OR THE LIKE

Richard W. Greger, Corning, N.Y., assignor to Corning Glass Works

Filed Nov. 19, 1973, Ser. No. 417,223

Term of patent 14 years

Int. Cl. D7—06

U.S. Cl. D7—130

Fig. 1

Fig. 2

Fig. 3

Fig. 4

FIG. 1 is a top plan view of a serving cradle or the like embodying my new design.

FIG. 2 is an end elevational view partially in section taken along line 2—2 of FIG. 1.

FIG. 3 is a bottom plan view.

FIG. 4 is a side elevational view partially in section taken along line 4—4 of FIG. 3.

I claim:

The ornamental design for a serving cradle or the like, as shown.
